WATER-HEATER.

1,244,183.

Specification of Letters Patent. Patented Oct. 23, 1917.

Application filed February 14, 1917. Serial No. 148,678.

To all whom it may concern:

Be it known that I, JOHN B. DUDLEY, a citizen of Canada, and residing at Detroit, in the county of Wayne and State of Michigan, have invented a new and Improved Water-Heater, of which the following is a specification.

This invention relates to means for heating water and other liquids and its object 10 is to provide a water heater of simple construction, that will be very compact, that can be constructed at low cost, and that will be efficient.

This invention consists in a horizontal 15 water chamber built up of three substantially circular disks joined together at their edges, the middle disk being substantially flat and the upper and lower disks being bulged outwardly and preferably constituting spherical segments, the middle member 20 constituting a diaphragm to separate the water chamber into two divisions but provided with an opening to permit free circulation between the two divisions, a feed 25 pipe to convey water to one of the divisions of said chamber, said pipe extending up through the lower head and connecting into an opening in the diaphragm, a second pipe to carry away the water from the other division and extending down through the upper 30 head and connecting into another opening in said diaphragm, and a burner mounted below the lower head. It also consists in providing a shell or housing extending 35 around said water chamber and said burner in such a manner that the hot gases from the burner will be forced to pass around the water chamber in close contact with substantially the entire surfaces of both the upper 40 and the lower heads. It further consists in means for preventing the upper and lower heads of the water chamber from separating more than predetermined distances from the diaphragm. It further consists 45 in forming the housing in two parts normally held together by means of springs, which springs permit the two parts of the housing to separate in case the pressure between them exceeds a predetermined 50 amount. It further consists in the details of construction shown in the drawings and especially set forth in the claims.

In the accompanying drawings Figure 1 is a central vertical section of this improved water heater. Fig. 2 is a section on the line

2-2 of Fig. 1. Fig. 3 is a transverse section of the edge of the water chamber.

Similar reference characters refer to like parts throughout the several views.

The three sheet metal disks, preferably 60 copper, constituting the water chamber are the upper head 3, the lower head 4 and the diaphragm 5 between the two heads. The edges of these three members may be secured together in any desired manner, but 65 preferably by rolling them onto each other, as shown in Fig. 3, and then uniting by means of soldering, brazing or welding. The two heads 3 and 4 are bulged outwardly 70 from the diaphragm 5 and preferably constitute spherical segments. The lower head 4 is formed with a circular flange 6 at one side of the center into which the feed pipe 7 extends, which pipe also extends up into the circular flange 8 on the diaphragm 5. 75 A discharge pipe 9 is fastened at its lower end within the circular flange 10 on the diaphragm 5 and extends through the circular flange 12 on the head 3. These pipes 7 and 9 are united to the flanges 6, 8, 10 and 12 80 by soldering, brazing or welding in order that the joints may be absolutely tight. The discharge pipe 9 is preferably mounted centrally of the water chamber and directly over the burner.

Any desired means may be employed to prevent the heads 3 and 4 from being forced 85 too far apart by high pressures within the water chamber. In Fig. 1, a rod 15 is shown provided with a foot 16 united to the head 4 in any desired manner. The upper end of the rod 15 is formed with an eye 17 through which and the walls of the pipe 9 the pin 18 extends.

Surrounding the water chamber is a housing, preferably of cast iron, formed of the upper part 19 and the lower part 20, the latter being also expanded to form a combustion chamber 21 provided with any desired number of air inlet holes 22. Any desired means may be provided to hold the housing properly spaced from the water chamber. In Fig. 1, legs 23 formed on the upper part 19 of the housing are shown resting on the upper head 3 of the water chamber. Lateral movement between the housing and water chamber will be prevented by the pipes 7 and 9. The burnt gases may be carried off by means of an elbow 24 connected to the middle of the upper part 19 of 100 105 110 115 120 125 130 135 140 145 150 155 160 165 170 175 180 185 190 195 200 205 210 the housing. Studs 25 are shown screwed into the lower part 20 of the housing and extend up through holes in the upper part. Nuts 26 and springs 27 on these studs hold 5 these two parts of the housing firmly together, but should an explosion occur within the housing, these springs 27 will yield and permit the two parts of the housing to separate and the pressure to be relieved.

10 The burner shown in the drawing is only an example of what may be employed. Any other desired means may be used to apply heat to this water chamber. In the drawing the body 29 of an ordinary Bunsen burner 15 extends up through a hole in the combustion chamber and the head or ring 32 is connected to the upper end of this body. A perforated disk 33 of any desired character may be secured in this head or ring for the 20 purpose of causing the mixed gas and air to flow evenly from the burner. Gas may be supplied by means of a pipe 31. Because of the location of this burner immediately below the intake end of the discharge pipe 25 9, the water passing up into this pipe will be of maximum temperature. If desired, a nut 34 may be used to secure the burner in position.

As the water passes through the pipe 7 30 to the upper division of the water chamber and is there warmed before it enters the lower division, the head 4 will not be kept cold and condensation of the water vapor resulting from combustion will be avoided.

35 As the pipe 9 is directly above the burner, the hottest water will always be just at the inlet of this pipe. The curvature of the housing is such that the hot gases and flames will be directly in engagement with all of 40 the outer surfaces of the water chamber and maximum efficiency is attained.

I claim:—

45 1. In a water heater, the combination of a water chamber consisting of upper and lower outwardly convex heads and a substantially flat horizontal diaphragm between them, a pipe connecting into the space above the diaphragm to supply water thereto, said diaphragm having a hole through which 50 said water may pass to the space below it, a burner below the lower head, and a housing extending around the burner and then around the water chamber with its walls substantially parallel to the outer portion 55 of the lower head and to the upper head to cause the burnt gases to flow in engagement with said surfaces of the water chamber.

60 2. In a water heater, a water chamber consisting of two substantially spherical heads and a substantially flat diaphragm between them, a feed pipe passing through the lower head and connecting into the diaphragm to supply water to the space above the diaphragm, said diaphragm having an 65 opening to permit the water above it to

flow to the space below it, and a pipe passing down through the upper head and connecting into the diaphragm to convey away the water in the space below the diaphragm.

3. In a water heater, a water chamber 70 consisting of two substantially spherical heads and a substantially flat diaphragm between them, a feed pipe passing through the lower head and connecting into the diaphragm to supply water to the space above 75 the diaphragm, said diaphragm having an opening to permit the water above it to flow to the space below it, a pipe passing down through the upper head and connecting into the diaphragm to convey away the water in 80 the space below the diaphragm, a burner below the water chamber, and a housing inclosing the chamber and having its upper portion extending parallel to the upper head of the chamber.

4. In a water heater, the combination of a water chamber consisting of upper and lower heads and a substantially horizontal diaphragm between the heads, a feed pipe extending through the lower head and diaphragm, a discharge pipe extending through the upper head and diaphragm, said diaphragm having an opening to permit water to pass, a housing around the water chamber comprising an upper portion substantially 95 parallel to the upper head and provided with means to carry off the burnt gases and a lower portion substantially parallel throughout most of its area to the lower head and having a central combustion chamber, and a 100 burner in said combustion chamber.

5. In a water heater, the combination of a water chamber consisting of upper and lower heads and a substantially horizontal diaphragm between the heads, a feed 105 pipe extending through the lower head and diaphragm, a discharge pipe extending through the upper head and diaphragm, said diaphragm having an opening to permit water to pass, a housing around the 110 water chamber comprising an upper portion substantially parallel to the upper head and provided with means to carry off the burnt gases and a lower portion substantially parallel throughout most of its area to the lower 115 head and having a central combustion chamber, a burner in said combustion chamber, and resilient means to hold the two portions of the housing together but permitting them to separate.

6. In a water heater, a water chamber consisting of two substantially spherical heads and a substantially flat diaphragm between them, a feed pipe passing through the lower head and connecting into the diaphragm to 125 supply water to the space above the diaphragm, said diaphragm having an opening to permit the water above it to flow to the space below it, a pipe passing down through the upper head and connecting into the dia- 130

phragm to convey away the water in the space below the diaphragm, and means to hold the central portions of said heads in fixed relation to each other.

5 7. In a water heater, a water chamber consisting of two circular heads convex away from each other and a substantially flat diaphragm between them provided with an opening to permit the flow of water, a feed 50 pipe passing through the lower head at one side of its center and connecting into the diaphragm, a discharge pipe passing through the center of the upper head and connecting into the diaphragm, and a burner below the 55 center of the lower head and said discharge pipe.

10 8. In a water heater, a water chamber consisting of two circular heads convex away from each other, and a substantially flat diaphragm between them provided with a single opening at one side of the center to permit the flow of water, a feed pipe connected into said water chamber at one side of the center so as to supply water to the space 20 above the diaphragm, said feed pipe and said opening in the diaphragm being substantially diametrically opposite each other and equally spaced from the center of the diaphragm so as to cause all the water to flow 25 across substantially the entire diameter of the diaphragm, a discharge pipe connected into said water chamber and extending vertically from substantially the middle of the space below the diaphragm so as to conduct 30 water upwardly therefrom, and means to heat the lower head of the water chamber.

35 9. In a water heater, a water chamber consisting of two circular heads convex away from each other, and a substantially flat diaphragm between them provided with a single opening at one side of the center to permit the flow of water, a feed pipe connected into said water chamber at one side of the center so as to supply water to the space 40 above the diaphragm, said feed pipe and said opening in the diaphragm being spaced apart in a diametrical line and near the edges of said diaphragm so as to cause the water entering said chamber to pass entirely across the diaphragm, a discharge pipe connecting into said water chamber below the diaphragm, and means to heat the lower head of the 45 water chamber.

45 10. In a water heater, a water chamber consisting of upper and lower heads, a diaphragm between them provided with a single opening to permit the flow of water, a feed pipe connecting to said water chamber so as to supply water to the space above the diaphragm, said feed pipe and said opening in the diaphragm being spaced apart in a diametrical line and near the edges of said diaphragm so as to cause the water entering said chamber to pass entirely across the diaphragm, a discharge pipe connecting into said water chamber below the diaphragm, and means to heat the lower head of the water chamber.

JOHN B. DUDLEY.
